GARMENT HANGER

Roderick E. Franco, New York, N. Y.

Application September 16, 1950, Serial No. 185,199

6 Claims. (Cl. 223—91)

1

This invention relates to garment hanger structures and more particularly to supporting structures which may be selectively used for jackets and coats and/or for trousers.

It is one of the objects of the invention to provide means affording a simple, effective and compact garment hanger structure which is well balanced and ensures excellent gripping facilities to thereby prevent slipping or displacement of garments, in particular of trousers, with respect to the hanger or support.

It is another object of the invention to provide means rendering the possibility of detachably connecting with one another, and employing independently of each other the trouser or skirt holding part and the jacket or coat supporting part of the garment hanger, whereby great economy and simplified assembly of the hanger structure is achieved.

It is a further object of the present invention to provide means facilitating speedy closing and opening of the trouser or skirt receiving part and in a positive manner without resorting to lever, spring and similar elements which are generally characteristic of complicated and expensive hanger structures.

Still another object of the invention resides in the provision of means contributing to an aesthetic and pleasing shape of the hanger structure whose shoulder supporting portions may be sufficiently wide and suitably curved, thus providing therebelow space for accommodation of the trouser or skirt supporting portion and incorporation of the latter into the hanger structure assembly.

It is a still further object of the invention to provide means conducive to a sturdy and practical garment hanger structure, in which the trouser or skirt receiving support or portion extends transversely of or across the lower extremities of the coat or jacket supporting hanger portion, braces the latter, and is capable of holding at least one pair of trousers or one skirt at either side of the transversely extending trouser support.

With these and other objects in view, the invention will be hereinafter more fully described and the combination and arrangement of parts will be shown in the accompanying drawing and pointed out in the claims which form part of the specification.

In the drawing:

Fig. 1 is a side elevational view of the garment hanger embodying the features of the present invention with one end portion broken away to

2

show the connection of the trouser holding parts therewith;

Fig. 2 is a transverse sectional view taken generally on line 2—2 of Fig. 1;

Fig. 3 is an enlarged vertical sectional view taken on line 3—3 of Fig. 1;

Fig. 4 is a side elevational view of a modified form of the invention showing a trouser hanger with the end plates connected thereto;

Fig. 5 is a vertical sectional view taken on line 5—5 of Fig. 4; and

Fig. 6 is a fragmentary perspective view of the end plate assembly.

Referring now particularly to Figs. 1, 2 and 3, there is disclosed a garment shoulder hanger structure 10 having an upper portion 11 with a hanger hook 12 connected thereto and downwardly inclined portions 13 and 14 extending from portion 11 and forming the arms of the structure. Each of these downwardly inclined portions or arms terminates in an enlarged end portion 15 on which the shoulders of a coat or garment come to rest so as to maintain the shoulder shape of the garment and because of these end portions being suitably rounded, elongated and enlarged they are also adapted to conveniently receive a pants or trouser hanger bar arrangement 16. Each of the end portions 15 are provided with a U-shaped recess or cavity 17 into which the ends of the bar arrangement 16 may extend and be housed. These cavities or cutouts 17 are sufficiently large to permit access of the fingers of a person for the operation of turn wheels 18 and 19 which are arranged to project somewhat out of the cavities, as seen in Figs. 1 and 3.

The bottom of the recess 17 forms a base plate 21 integral with end portions 15 and the open sides of each U-shaped recess are closed by detachable plates 22 and 23. The detachable plates are secured to the respective enlarged end portion 15 by upper screws 24 while the lower ends of the plates 22 and 23 are respectively secured to base plate 21 by screws 25.

Extending under the hanger portion 11 and from one cavity or recess to the other is an intermediate or fixed bar 26. The upper edge of bar 26 may be seated in a corresponding groove 27 provided in the top surface 15a defining recess 17. The bar 26 is further held in position against the base plate 21 by screws 28.

Extending through an opening 26a in each end of the intermediate bar 26 is a fast screw threaded shaft 31 having respectively squared

ends 32 engaged in square openings 33 of the side plates 22 and 23.

Extending between the fast threaded shafts and slidably thereon are movable trouser or skirt supporting bars 34 and 35. Turn wheels or adjusting means 18 and 19 are, respectively, associated with these bars 34 and 35 and serve to move the bars along threaded shafts 31 toward the main fixed bar 26 whereby to clamp trousers 36 thereagainst and to hold the same from dropping from the movable bar. The upper edge of the movable bars are, respectively, rounded, as indicated at 37, to accommodate the trousers or skirt and to eliminate any possibility of placing a crease therein. The turn wheels 18 and 19 are easily accessible and can be turned in either direction quickly and easily to either connect the trousers or skirt to the hanger or disengage the same therefrom.

Referring now particularly to Figs. 4, 5 and 6, there is shown a modified form of the invention wherein the main hanger and inclined portions are dispensed with and the hanger hook, as indicated at 40, is directly connected to an intermediate trouser or skirt hanger bar 41. In order that coats and the like can be extended over the trouser hanger, removable plate assemblies 42 are respectively connected to the opposite ends of the intermediate bar 41. Each plate assembly comprises a block 43 (Fig. 6), having a recess 44 therein, the ends of which are closed by plates 45 and 46 respectively connected to the block 43 by screws 47. The plates 45 and 46 have square openings 48 respectively therein for receiving squared ends 49 respectively of a fast threaded shaft 50. There is one of these shafts extending across and at each end of the main or intermediate bar 41.

Movable in lengthwise direction of these fast threaded shafts are hanger bars 51 and 52 which may be brought into tight engagement with a skirt or a pair or pairs of trousers hanging thereover, respectively, by first shifting these movable bars against fixed bar 41 and then by turning wheels or adjusting means 53 and 54 which are operatively connected to the fast threaded shafts, as is well understood. Each plate assembly 42 is made secure upon the end of the intermediate fixed bar 41 by groove 55a and also by a screw 55 extending upwardly into bar 41 from the bottom of the block 43 and through opening 56 therein.

At times when it is desired to use the trouser hanger independently of the plate assemblies 42, the plate assemblies can be readily removed by simply releasing the screw 55 from the intermediate bar 41. With the assemblies 42 in place, however, the hanger is adaptable for both coats and the like and for trousers or skirts.

It will be realized from the above disclosure that the trouser supporting means may be manufactured independently of the coat shoulder supporting means 11 to 15 inclusive, and can be either used separately in connection with blocks 42 or may be inserted in U-shaped recesses or cavities of the coat or garment shoulder supporting means to thereby form an integral part of the latter. Thus, great economy and simplified assembly of the complete hanger structure is attained.

It can thus be seen that there has been provided in accordance with this invention a garment hanger device which comprises, in combination, a coat shoulder supporting portion in-

cluding downwardly diverging arms each provided with an end of enlarged surface and a cavity therebelow, trousers engaging means extending across said ends of said diverging arms and engageable therewith in said cavities, and fastening means removably retaining said trousers engaging means on said coat shoulder supporting portion to brace the latter.

Having thus described the invention, what is claimed as new and desired to be secured by Letters Patent, is:

1. A garment hanger structure having shoulder portions; comprising an assembly of a transversely extending bar, with means connected to opposite ends of said bar for supporting coats and like garments at the shoulder portions thereof, hook means for suspending the assembly, each of said end means having a recess therein and receiving an end of said bar, a fast threaded shaft extending across each recess and through the respective end of said bar and fixed to said shoulder portions, an adjustable clamp bar extending between the fast threads, and wheel means operable upon the ends of said clamp bar and upon the fast threads to effect engagement of said clamp bar against said garment extending thereover and to force the same against the transverse bar of the assembly.

2. A garment hanger structure comprising an assembly of a main transverse bar, with end shoulder means releasably connected to opposite ends of said main transverse bar, hook means connected to said assembly for securing the hanger structure to a supporting member, said end shoulder means comprising each a portion having a recess therein, the ends of said transverse bar entering the respective recesses, fast threaded shafts extending across the recesses and secured against rotation upon the end shoulder means, an adjustable bar having its ends connected between the respective fast threaded shafts and movable thereupon, and a turn wheel on each shaft to adjust the adjustable bar whereby the garment extended between the transverse bar and the adjustable bar may be secured therebetween against downward displacement therefrom.

3. A garment hanger structure comprising a main portion having downwardly inclined arms terminating in enlarged end shoulder portions, each of said shoulder portions having a recess therein, side plates removably secured to opposite ends of the shoulder portions, a bottom plate secured to said side plates for closing the bottom of each recess, a fast threaded shaft extending between the side plates of each shoulder portion, a main transverse bar supporting said shafts and respectively connected to said arms of said main portion, an adjustable bar carried by said shafts and movable thereover relative to said main transverse bar, to secure a garment between the adjustable bar and said main bar, and means operable upon the fast threaded shafts and engageable with the adjustable bar for effecting clamping engagement of the same with the garment and said main bar.

4. A garment hanger structure comprising a fixed main bar having a hook extending upwardly therefrom for the attachment of the garment hanger structure to a support, an end plate assembly to adapt the hanger for use in supporting coats and like garments from their shoulder parts thereof, each of said plate assemblies comprising a block, side plates connected to the opposite sides of the block, each block having a recess

adapted to receive the respective end of the main bar, means releasably securing said end plate assemblies to said bar so that the ends of the bar are confined within the recesses of the end plate assemblies, each of said assemblies having a fast threaded shaft extending through said main bar and between said side plates, a movable bar on at least one of said fast threaded shafts, and wheel means associated, respectively, with each fast threaded shaft to effect clamping engagement of said movable bar with a garment thereon and with said main bar.

5. A garment hanger device comprising a coat supporting portion having a median part with downwardly diverging arms, the ends of said arms of said supporting portion being provided with cavities, trousers engaging bars extending into and between said cavities, and rotatable means including threaded means extending across said cavities and retaining said bars therein, said rotatable means engaging said threaded means laterally of said trousers engaging bars, to thereby grip said trousers thereon in crosswise direction to said bars.

6. A garment hanger device comprising, in combination, a coat shoulder supporting portion including downwardly diverging arms each pro-

10 vided with an end of enlarged surface and a cavity in each enlarged surface therebelow, trousers engaging means extending across said ends of said diverging arms and engageable therewith in said cavities, and threaded means including adjusting means thereon, said threaded means retaining said trousers engaging means in said cavities and being adapted to facilitate displacement of said adjusting means and said trousers engaging means relative to each other and to said coat shoulder supporting portion, whereby trousers placed on said trousers engaging means are secured on the latter upon displacement of said adjusting means on said threaded means in the direction toward said trousers engageable means.
